UNITED STATES PATENT OFFICE.

WARD W. WILLITS, OF CHICAGO, ILLINOIS, ASSIGNOR TO THE ADAMS & WESTLAKE COMPANY, OF ILLINOIS.

LAMP.

SPECIFICATION forming part of Letters Patent No. 427,491, dated May 6, 1890.

Application filed December 10, 1889. Serial No. 333,267. (No model.)

To all whom it may concern:

Be it known that I, WARD W. WILLITS, of Chicago, in the county of Cook, in the State of Illinois, have invented certain new and 5 useful Improvements in Lamps, of which the following is a specification.

My improvement relates to hanging or chandelier lamps—such as are used for lighting railway-cars—in which a central hanger is 10 used for supporting a number of burners.

The object of my invention is to add to the general availability of the lamp by adapting it for use as either a side or center lamp, to increase the accessibility of the oil-founts 15 and the burners, and to provide a secure fastening for them when in use; and, further, to improve the appearance of the lamp as a whole and interfere with the radiation of light from the burner as little as possible.

20 In the accompanying drawings, Figure 1 is a side elevation of the lamp. Fig. 2 shows the lower end of the hanger. Fig. 3 is a view of the inner side of an oil-fount. Fig. 4 is a section on line $x x$, Fig. 2.

25 A is the hanger, which depends from the roof or ceiling. The arms B B, which carry the shades C C, extend from the hanger A. The lower part of the hanger A is flattened. and an undercut groove D is made in each

30 of its flat faces, and into each groove a projection E on the lamp-fount F is fitted. Ears e e are formed on each side of the projection E, and corresponding notches d d are made in the side of the undercut groove D. The

35 fount F is secured by placing the ears e e opposite the notches d d and inserting the projection E into the groove D. The fount is then allowed to slide down, the ears e e catching under the sides of the groove D. A

40 spring-catch G engages in a notch e' in the fount and holds it securely in place. The opposite side of the hanger A being similarly grooved and provided with a spring-catch H, corresponding to the catch G, the same fount will fit either side.

45 Branching from each of the founts F, arranged about the central support, is an arm I, at the outer end of which is a burner J.

By connecting the fount and burner together and making them detachable as a whole, and 50 by providing separate founts for the burners on opposite sides of the central support, I secure the recognized advantages of appearance and absence of downwardly-cast shadows resulting from the use of a central 55 oil-fount, while the portability of each light (ordinarily secured by mounting the burner on the fount and supporting both at the outer ends of the arms branching from the center) is also retained. By providing a fixture 60 in the side of the car or wall, grooved in the same manner as the lower end of the center hanger, any of the burners may be used as a side lamp, its use in a temporary way being often very convenient in situations 65 where a permanent side lamp or a projecting fixture would not be desirable.

I am aware that it is not new, broadly, to provide a number of oil-founts, each having an outwardly-branching arm to which is attached a burner, such a construction being shown in the patent to Harrison, No. 232,961; but in securing the founts by fastenings at its side rather than at its bottom the purposes of my invention are better attained; 70 the fastening may be made more secure, because it may extend the length of the oil-fount instead of only beneath it; the fastening is less liable to rattle, and the oil-fount is united closely to the central standard, so 75 that the founts and standard or hanger present to the eye the appearance of a single object, giving a more pleasing effect, and the lamp is much better adapted for transfer- 80 ence and use as a side light, no projection 85 extending beneath the founts being necessary, such projections being undesirable in a side-lamp fixture.

What I claim, and desire to secure by Letters Patent, is—

1. In a chandelier-lamp, the combination of a central hanger consisting of a single downwardly-projecting standard, a plurality of oil-founts detachably secured thereto directly by fastenings to their sides, and out- 95 wardly-branching arms from said founts pro-

vided with burners at their outer ends, substantially as described.

2. The combination, in a chandelier-lamp, of a central hanger having flattened grooved 5 faces on its lower end, a corresponding number of oil-founts having projections fitted to said grooves, and arms branching from said

founts and having burners at their outer ends, substantially as described.

WARD W. WILLITS.
